United States Patent Office

Des. 178,030
Patented June 12, 1956

178,030

DISPLAY PACKAGE FOR A WATCH BAND OR THE LIKE

Max E. Westerman, New York, N. Y.

Application October 28, 1955, Serial No. 38,623

Term of patent 3½ years

(Cl. D80—5)

Fig. 1.

Fig. 2.

I claim:

The ornamental design for a display package for a watch band or the like, as shown.
